SPINNING FRAME FOR MAKING NOVELTY YARN

Frank Everett Nutter and Ernest I. Spence, Sanford, Maine, assignors to Goodall Worsted Company, Sanford, Maine, a corporation of Maine

Application December 26, 1941, Serial No. 424,464

3 Claims. (Cl. 57—38)

This invention relates to the manufacture of so-called "novelty" yarn.

One object of the invention is to provide for creating the novelty effect in the yarn in the spinning frame on which the yarn is spun and simultaneously with the spinning operation.

One common way of making a novelty yarn is to twist together in a twister frame, two or more ends or strands which may be of different colors and/or of different material and/or both; and one way of providing a novelty effect is to feed one of the ends or strands into the twister frame at a faster rate than the other end or strand with the result that the strand which is fed faster will be wrapped about the other strand in an irregular or random manner, some of the turns of the faster-fed strand being relatively close together and other turns being widely separated. Such ends or strands may be in the form of spun yarn or filament yarn.

To produce a novelty yarn in this way where the strands are of spun yarn, necessitates that each yarn shall first be spun on a spinning frame and that after the yarns have been spun, the spun yarns shall be transferred to a twister frame for the doubling operation.

As stated above, one object of the present invention is to provide means whereby the doubling operation to produce the novelty effect may be carried out on the spinning frame simultaneously with the spinning operation thereby obviating the necessity of subjecting the strands to a separate additional doubling operation on the twister frame as has heretofore been necessary.

In carrying out our invention, we employ a spinning frame having the usual drafting mechanism by which the roving is drafted to produce a drafted roving of substantially uniform size and also having the usual means for twisting the drafted roving to form a yarn of substantially uniform size and winding it on a yarn carrier, and we provide the spinning frame with means for feeding at a uniform rate a prepared novelty-producing strand directly to the drafted roving of uniform size while it is being twisted and while it is traveling from the drafting mechanism to the yarn carrier so that the said strand will be twisted or doubled with the drafted roving while the spinning twist is being put into the latter and in such a way as to produce the desired novelty effect. This novelty-producing strand is preferably fed to the drafted roving at a speed different from that at which said drafted roving is being delivered from the front rolls. If the strand is fed to the drafted roving

at a faster speed than the traveling movement of said roving while the spinning twist is imparted thereto, then the strand will be wrapped around the drafted roving as it is being twisted and the turns of the strand will have an irregular or random arrangement, thus giving the desired novelty effect.

This novelty effect is thus produced on the spinning frame and during the spinning operation so that the yarn which accumulates on the yarn carrier of the spinning frame is a novelty yarn and requires no further manipulation or treatment to produce the novelty effect. This prepared novelty-producing strand may be a spun yarn or a filament yarn or a strand of any other suitable character.

In order to give an understanding of the invention we have illustrated in the drawings some embodiments thereof which will now be described, after which the novel features will be pointed out in the appended claims.

In the drawings,

Fig. 1 is a sectional view of a spinning frame embodying my invention.

Fig. 2 is a view similar to Fig. 1 but showing a spinning frame adapted to make a different form of novelty yarn from that illustrated in Fig. 1.

Fig. 3 is a somewhat diagrammatic view illustrating the gearing for driving the rolls of the drafting apparatus and the feed rolls for feeding the spun yarn to the drafted roving.

Figs. 4, 5, and 6 are enlarged views showing different forms of novelty yarn which may be produced in accordance with this invention.

Fig. 7 is a fragmentary detail view showing the manner of mounting the feed rolls.

Referring first to Fig. 1, 1 indicates a spinning frame having the usual drafting apparatus 2 by which the roving 4 to be spun is drafted to produce a drafted roving of substantially uniform size, and also having the usual twisting and winding apparatus indicated generally at 3, by which the spinning twist is put into the drafted roving to produce a spun yarn of substantially uniform size and the spun yarn is wound on a yarn carrier 24.

The drafting apparatus 2 of the spinning frame may have any suitable or usual construction depending somewhat on the character of the fibres of which the roving 4 to be drafted and spun is composed.

In the illustrated embodiment of the invention, this drafting apparatus comprises the upper and lower back rolls 5 and 6, the upper and lower

front rolls 7 and 8, the intermediate carrier rolls 9 and cooperating tumbler rolls 10. This is the type of drafting apparatus commonly known as the "worsted type" that is used for drafting relatively long fibres, but if the roving 4 is composed of relatively short fibres, then a drafting apparatus suitable for such shorter fibres would be used. In any event the drafting apparatus is of some usual type which produces a drafted roving of substantially uniform size.

The twisting and winding device 3 by which the spinning twist is put into the drafted roving after it is delivered from the front rolls 7 and 8, and by which the yarn is wound on the yarn carrier 24, may be of any usual kind such as ring spinning device, cap spinning device, or a flyer. Merely for illustrative purposes, we have shown herein a twisting and winding apparatus of the cap spinning type.

40 indicates the ordinary fly board which is commonly used on spinning frames for guiding the yarn during the spinning and winding operation.

In order to produce a novelty yarn on the spinning frame, we provide said frame with means for feeding a prepared novelty-producing strand 11, such as a spun yarn or a filament yarn, to the drafted roving 4, which is of substantially uniform size, at a point between the front rolls 7, 8 and the twisting and winding device 3 and while the spinning twist is being put into said drafted roving, said prepared strand or yarn being twisted with the drafted roving in such a way as to produce the desired novelty effect. This strand 11, which is shown as being taken from a spool 12 carried by the spinning frame, is fed positively to the drafted roving 4 by means of suitable feed rolls 13, 14 which are situated in front of the front roll 7 in position to deliver the strand 11 directly to the drafted roving 4 between the front rolls and the fly board 40.

One or both of the feed rolls 13, 14 is positively driven and said rolls constitute means for positively feeding the novelty-producing strand 11 directly to the drafted roving 4. Said feed rolls are positively operated so as to feed the novelty-producing strand to the drafted roving 4 at a uniform speed different from that at which the drafted roving is moving forward.

Since the novelty producing strand 11 is being delivered positively from the feed rolls 13, 14 directly to the drafted roving 4 at a uniform speed, the portion of said strand between the feed rolls and the drafted roving will be under a uniform tension. Said strand 11, therefore, is delivered directly to the drafted roving 4 under a uniform tension.

This strand 11 may be made of any desirable material and may have any desirable color depending upon the novelty effect which it is desired to produce, and as stated above, it may be a spun yarn or a filament yarn or a strand of any other suitable character.

If the strand 11 is fed to the drafted roving 4 at a speed faster than that at which the drafted roving is delivered from the front rolls, then said strand 11 will be wrapped more or less loosely around the twisted roving 4 and the turns of the strand will have an irregular or random arrangement something as illustrated in Fig. 5, wherein 4 indicates the drafted roving of uniform size which has been twisted by the twisting and winding apparatus 3, and 11 indicates the strand which is wrapped about the twisted roving

4, thereby producing a novelty yarn 25. As stated above, the turns of the strand 11 will have an irregular or random arrangement, some of the turns being quite close together as indicated at 19 and other turns being widely separated as indicated at 20. If the strand 11 is of a different color from the strand 4, the novelty effect produced by the irregular or random arrangement of the turns of the colored strand 11 will be enhanced.

If the strand 11 is being delivered from the front rolls 7 and 8 at the same speed as the drafted roving 4 then the twisted roving 4 and the strand 11 will be twisted together quite regularly as illustrated in Fig. 4.

If the strand 11 is delivered to the drafted roving 4 at a slower speed than that at which the roving is delivered from the front rolls 7 and 8, then the tendency will be for the twisted roving to wrap itself around the strand 11 and a still different novelty effect will be produced.

In any event, the novelty effect of the yarn 25 is produced by the way in which the novelty-producing strand 11 is twisted with the spun yarn that is formed by imparting the spinning twist to the drafted roving 4, and such novelty yarn will have much the same effect as would be produced by doubling or twisting together two spun yarns in a twister frame, but as the novelty effect is produced directly on the spinning frame, the necessity of any subsequent manipulation of the yarns after removal from the spinning frame in order to create the novelty effect is obviated.

The feed rolls 13 and 14 are positively driven and may be operated in any convenient way. As herein shown, the lower roll 14 is a driven roll while the upper roll 13 is in the form of an idler which is rotated by its frictional contact with the driven roll 14.

In Fig. 3, we have illustrated a schematic layout for driving the various rolls of the drafting apparatus and also for driving the feed roll 14. In said Fig. 3, 21 indicates a shaft on which the bottom front rolls 8 are mounted and which is driven from any suitable driving gear 22 at a uniform speed as usual in drafting apparatus.

This shaft is connected to the shaft 23 on which the back rolls 6 are mounted by any usual system of gearing 26 which includes a gear 32 fast on the shaft 21. The feed roll 14 is a relatively long roll which is geared to and is driven from the shaft 21. For this purpose, said roll 14 has a gearing 27 rigid therewith which meshes with a gear 28 carried by a shaft 29, the latter having another gear 30 thereon which meshes with an intermediate gear 31 that in turn meshes with and is driven by the gear 32. A plurality of upper rolls 13 may be provided, one for each of the front rolls 8 and these rolls 13 are shown as provided at their ends with trunnions 44 which are received in bearing slots formed in upstanding arms 45 which are carried by a suitable supporting bracket 46 that is attached to the frame.

The gears 27 and 28 are interchangeable for gears of different sizes so that by removing the gears and replacing them by other gears of different size, the surface speed of the feed rolls 13 and 14 may be varied with regard to the surface speed of the front rolls 7 and 8 and thereby means are provided for rotating the feed rolls 13 and 14 either faster or slower or at the same surface speed as that at which the front rolls 7 and 8 are rotated. Said feed rolls 13, 14 are thus positively driven at a controlled speed, and

the strand 11 will be delivered directly to the drafted roving 4 under uniform tension.

In Fig. 2, we have illustrated a different embodiment of the invention in which the novelty yarn is composed of three strands instead of the two strands illustrated in Fig. 1. In the device of Fig. 2, provision is made not only for feeding a spun yarn or other strand to the drafted roving to be twisted therewith, but also for feeding a third strand, either in the form of a spun yarn or a filament yarn, or in the form of a drafted roving, to the front rolls immediately in the rear thereof, which third strand is fed through the front rolls with the drafted roving 4. This third strand, which is indicated at 33, is twisted with the drafted roving 4 while the two strands are traveling from the front rolls to the point where the strand 11 is added to produce the novelty effect, and from this point to the yarn carrier the three strands will be twisted together. If the strand 11 is being fed by the feed rolls 13 and 14 faster than the combined drafted roving 4 and the other strand 33 is being delivered from the front rolls, then said strand 11 will be wrapped around the other two strands and the turns of the strand 11 will have an irregular or random arrangement as indicated in Fig. 6, some of the turns of the strand 11 being relatively close together as indicated at 34 and other turns being more or less widely separated as indicated at 35, thereby producing the novelty effect.

By making the necessary changes in the sizes of the gears 21 and 28, the speed with which the feed rolls 13 and 14 deliver the strand 11 may be changed so that it will be the same as, or even slower than the speed at which the two strands 4 and 33 are delivered from the front rolls 7 and 8 and thereby the novelty effect of the completed yarn will be varied.

Our invention, therefore, provides a novel spinning frame adapted to produce a novelty yarn by feeding at a controlled speed a prepared novelty-producing strand to a drafted roving of uniform size at a point where the spinning twist is being put into said drafting roving, and it also provides a novel method for thus making a novelty yarn.

We claim:

1. A spinning frame for producing a novelty yarn comprising means, including front rolls, back rolls and means to rotate said rolls at uniform surface speeds, to draft a roving and deliver the drafted roving from the front rolls at a uniform rate to produce a drafted roving of uniform size, means for imparting a spinning

twist to said drafted roving, a pair of feed rolls situated in front of the front roll to deliver a novelty-producing strand directly to the drafted roving at a point where the spinning twist is being imparted thereto, and means to rotate the feed rolls at a uniform surface speed which is different from that of the front rolls whereby the novelty-producing strand is delivered directly to the drafted roving at a uniform rate and under uniform tension.

2. A spinning frame for producing a novelty yarn comprising means, including front rolls, back rolls and means to rotate said rolls at uniform surface speeds, to draft a roving and deliver the drafted roving from the front rolls at a uniform rate to produce a drafted roving of uniform size, means for imparting a spinning twist to said drafted roving, a pair of feed rolls situated in front of the front roll to deliver a novelty-producing strand directly to the drafted roving at a point where the spinning twist is being imparted thereto, and means to rotate the feed rolls at a uniform surface speed which is faster than that of the front rolls whereby the novelty-producing strand is delivered directly to the drafted roving under uniform tension and at a uniform rate which is faster than that at which the drafted roving is being delivered from the front rolls, and said novelty-producing strand and drafted roving will become irregularly twisted together to produce a novelty effect.

3. A spinning frame for producing a novelty yarn comprising drafting apparatus, including back rolls and front rolls, for drafting a roving, means to deliver directly to the front rolls on the input side thereof a strand separate from the drafted roving, means for imparting a spinning twist to said combined drafted roving and strand, thereby to produce a spun yarn and to wind said spun yarn on a yarn carrier, a pair of feed rolls situated in front of the front rolls to deliver a prepared novelty-producing strand directly and positively to the combined drafted roving and first-named strand at a point where the spinning twist is being imparted thereto, means to rotate said feed rolls at a uniform surface speed which is different from the surface speed of the front rolls whereby the novelty-producing strand is delivered directly to the combined drafted roving and first-named strand under uniform tension and said novelty-producing strand is irregularly twisted with the spun yarn to produce a novelty effect.

FRANK EVERETT NUTTER.
ERNEST I. SPENCE.
